TEMPERATURE HUMIDITY INDEX INSTRUMENT

Edward G. Solecki, Chicago, and Richard W. Lanigan,
Arlington Heights, Ill.; said Richard W. Lanigan,
assignor to said Edward G. Solecki

Filed June 5, 1963, Ser. No. 75,221

Term of patent 14 years

(Cl. D52—7)

FIG. 1

FIG. 2

FIG. 3

FIG. 1 is a front elevational view of a temperature humidity index instrument, showing our new design;

FIG. 2 is a side elevational view thereof, with a portion of the housing partly broken away and shown in section; and

FIG. 3 is a rear elevational view thereof, with the stand broken away for convenience of illustration.

We claim:

The ornamental design for a temperature humidity index instrument, substantially as shown.
